UNITED STATES PATENT OFFICE

158,781

FLUORESCENT LIGHTING FIXTURE

Carl X. Meyer, St. Louis, Mo., assignor to Day-Brite Lighting, Inc., St. Louis, Mo., a corporation of Missouri

Application September 1, 1949, Serial No. 4,804

Term of patent 14 years

(Cl. D48—23)

To all whom it may concern:

Be it known that I, Carl X. Meyer, a citizen of the United States and a resident of the city of St. Louis and State of Missouri, have invented a new, original, and ornamental Design for Fluorescent Lighting Fixture, of which the following in a specification, reference being had to the accompanying drawing, forming part thereof.

Fig. 1 is a bottom perspective view of a fluorescent lighting fixture, showing my new design.

Fig. 2 is an elevational view of the side opposite to that shown in Fig. 1.

Fig. 3 is an enlarged elevational view of the end opposite to that shown in Fig. 1,

Fig. 4 is a top plan view of the fixture; and

Fig. 5 is an enlarged vertical cross-sectional view on the line 5—5 in Fig. 2.

I claim:

The ornamental design for a fluorescent lighting fixture, substantially as shown.

CARL X. MEYER.
